UNITED STATES PATENT OFFICE.

WILLIAM L. BARLOW, OF CLEAR LAKE, IOWA.

CRATE FOR CATCHING AND HOLDING HOGS.

Application filed June 4, 1921. Serial No. 475,036.

To all whom it may concern:

Be it known that I, WILLIAM L. BARLOW, a citizen of the United States, residing at Clear Lake, in the county of Cerro Gordo, 5 and State of Iowa, have invented certain new and useful Improvements in Crates for Catching and Holding Hogs; and I do declare the following to be a full, clear, and exact description of the invention, such as 10 will enable others skilled in the art to which it appertains to make and use the same.

This invention relates to an improved crate for catching and holding hogs and one object of the invention is to provide a crate 15 so constructed that it may be easily entered by the hogs and further provided with improved means for engaging and holding the hogs, the hogs being securely clamped in the crate and one element of the clamping means 20 engaging the back of the hog so that the crate may be turned to an upside down position and the bottom of the crate then swung to an open position, the means for engaging the back of the hog serving as supporting 25 means for the hog when the crate is turned over and the bottom opened.

Another object of the invention is to provide an improved type of clamping board for engaging one side of the hog and improved means for moving this clamping board into position to clamp the hog against 30 a stationary side wall of the crate.

Another object of the invention is to provide improved means for slidably mounting 35 an upper wall for the crate between the clamping board and stationary side wall so that this upper wall section may be moved downwardly into engagement with the back of the hog.

40 Another object of the invention is to provide improved means for holding the upper wall in a depressed position when moved into engagement with the back of a hog, the means securing the upper wall section in 45 a depressed position constituting supporting means for the upper wall and thus supporting the weight of the wall section and hog when the crate is turned and the bottom swung to an open position.

50 Another object of the invention is to provide a crate so constructed that hogs of varying sizes may be secured in the crate and be positioned in approximately the same position when the crate is turned and the bottom swung to an open position.

Another object of the invention is to pro-

vide improved means for rotatably mounting the crate, this means consisting of improved circular track members carried by the crate and improved cradle means engaged by the 60 circular track members.

Another object of the invention is to provide a hog holding crate which will be strong and durable and simple in construction and further easy to operate.

65 This invention is illustrated in the accompanying drawings, wherein:

Figure 1 is a view showing the improved crate in side elevation.

Figure 2 is a top plan view of the im- 70 proved crate.

Figure 3 is a transverse sectional view taken along the line 3—3 of Fig. 1.

Figure 4 is a longitudinal vertical sec- 75 tional view taken along the line 4—4 of Fig. 3.

Figure 5 is a view showing the crate in end elevation after being turned over and having the bottom swung to an open position.

80 Figure 6 is a view similar to Fig. 5 looking at the opposite end of the crate.

Figure 7 is a fragmentary view illustrating in detail the manner of mounting the clamping board for sliding movement.

85 Figure 8 is a transverse sectional view taken along the line 8—8 of Fig. 7.

Figure 9 is a fragmentary view showing in detail the manner of securing one of the rods for holding the upper wall member in a de- 90 pressed position.

Figure 10 is a transverse sectional view taken along the line 10—10 of Fig. 9.

This crate is provided with a base 1 which is rectangular in shape and is provided at its 95 ends with cradle members 2, the end portions of which extend upwardly as shown in Fig. 3. Rollers 4 are provided at the ends of the cradle members and intermediate rollers 5 are provided intermediate the width of the 100 base and together with the rollers 4 engage the circular track rings 6 which are carried by the end walls 7 of the housing. This housing is provided with side walls 8 and 9 and with a bottom 10 which is hinge- 105 dly connected with the side wall 8 as shown at 11 and provided with an upstanding side section 12 which forms a portion of the wall 9 and will be provided with latch pins 13 for engagement by the latching hooks 14 mounted upon a bar 15 forming a portion 110 of this wall 9. The upper bar 16 of this wall

9 is spaced from the lower bar 15, thus providing an open space in this wall for a purpose to be hereinafter brought out. Doors 17 and 18 are provided for the end walls which 5 will be in the form of open frames, and these doors are hingedly mounted and releasably held in a closed position by suitable latching means. One of these doors is of a flat construction and the second door which will 10 be at the exit end of the crate will be in the form of a screen covered with wire so that light may readily enter the crate and the hog have no fear of entering the crate. It will thus be seen that with the door 17 closed and 15 the door 18 open, the hog will readily enter the crate and move toward the exit door 17. The entrance door 18 can then be closed and the hog will be confined in the crate.

A clamping board 19 is positioned vertically in the housing and is provided with 20 hangers 20 which extend upwardly from the clamping board and are provided with outstanding arms 21 which extend between spaced track bars 22 mounted upon the end 25 walls 7. These outstanding arms 21 may be provided with rollers if so desired so that they will slide easily between the track bars. An upper wall section 23 is positioned between the clamping board 19 and wall 8 and 30 is slidably mounted for vertical movement by means of cross rods 24 connected with the ends of the upper wall 23 by brackets 25 and having their end portions formed into eyes so that these rods may be slidably mounted 35 upon rods 26 carried by the walls 8 and 9. Springs 27 are mounted upon these rods 26 beneath the eyes of the rods 24 and will serve to yieldably retain the upper wall in a raised position but permit of it being moved downwardly to engage the back of a hog in the 40 pen.

In order to move the clamping board into engagement with the side of a pig or hog after the animal has entered the housing and 45 the door 18 has been closed, there have been provided rocker shafts 28 and 29 which are journaled in bearings 30 carried by the bars 15 and 16 of the walls 9. Each of these 50 rocker shafts is provided with a lever arm 31 and these lever arms are connected by a link 32 so that when the shaft 28 is rotated through the medium of the handle extension 33, the shaft 29 will be similarly rotated. Board-engaging arms 34 which are curved 55 longitudinally extend from these shafts 28 and 29 above and below the lever arms 31 and extend into the crate with their free end portions engaging the clamping board. It will thus be seen that when the rocker shafts 60 are rotated to swing the arms 34 inwardly, they will act upon the clamping board and slide this clamping board toward the wall 8. They will not only slide the clamping board toward the wall to bring it into engagement 65 with the side of a hog in the pen but will

also have a tendency to swing the board and will thus serve to bring the board into firm engagement with the sides of the hog and at the proper angle. The hog will thus be firmly clamped between the board and the 70 wall 8 and will be securely held against movement. A chain 35 is connected with the handle extension 33 of the rocker shaft 28 and is formed of links, the proper one of 75 which may be brought down into engagement with the cleats 36 carried by the wall 8 in order to permit the operating means for the clamping board to be secured in a set position with the hog firmly clamped between this pressure board and the wall 8. 80

After the hog has been clamped between the wall 8 and clamping board 19, the movable wall or cover 23 will be pressed downwardly and the rods 37 will be passed through the proper set of aligned openings 85 38 and 39 formed in the board 19 and wall 8 so that these rods 37 will extend above the upper wall and retain it in engagement with the back of the hog as shown in Fig. 3. After the securing rods have been passed 90 through the openings 38 and 39, they will be turned so that the locking fingers 40 will be moved into position for engagement by the brackets 41 secured vertically upon the wall 8. Therefore, the rods 37 cannot accidentally slip out of the openings 38 and 39 and the wall 23 will be securely held in engagement with the back of the hog. When the upper wall is in the raised position, the rod or pins 37 may be passed through suitable 95 openings 38 and 39 so that they will extend beneath this wall and support it thus taking strain off of the springs. 100

After the hog has entered the housing and has been engaged by the clamping board 19 and upper wall 23, the housing can be rotated and turned from the position of Fig. 3 to that shown in Figs. 5 and 6. The latches or hooks 14 can now be swung to a released position and the bottom swung open as 110 shown. The hog will then be supported in an elevated position upon its back and can be readily operated upon. It will thus be seen that there has been provided a crate into which the hog can be easily driven and 115 means for gripping the hog and supporting it. It will be further noted that the device is so constructed that the hog will always be supported in an elevated position and that since the clamping board terminates short of the bottom 10 and further the lower portion of the wall 9 is carried by this bottom, the hog will be held in such a position that it may be readily reached. After the necessary 120 operation has been performed, the bottom will again be swung to a closed position and secured and the crate can then be rotated to the original position. The rods or pins 37 will now be removed and the cover will be moved to a raised position by the springs 27. 130

The exit door will now be opened and the chains released so that the clamping board will move out of binding engagement with the hog. The hog will thus be released and 5 may leave the housing through the exit end of the housing. The exit door will now be closed and the entrance door opened to permit another hog to enter the housing.

I claim:

10 1. An animal crate comprising a housing including a stationary side wall and a bottom releasably held in a closed position and movable to an open position when released, a clamping board movably mounted in the housing and movable toward and away from the stationary wall, an upper clamping element positioned between the clamping board and stationary wall and mounted for vertical movement and yieldably held in a 15 raised position and movable downwardly to engage the back of an animal, means for releasably holding the upper clamping element in a depressed position, means for moving the clamping board toward the stationary wall for clamping engagement with the side of an animal and holding the board in a clamping position, and movable closures for the ends of said housing.

2. The structure of claim 1 having the 20 means for moving the clamping board toward a clamping position consisting of rotatably mounted rocker shafts, arms extending from said rocker shafts and engaging said clamping board, one of the rocker shafts being provided with a turning element, and means for transmitting rotary movement from one shaft to the other.

3. The structure of claim 1 having the 25 stationary wall and clamping board provided with openings, vertically disposed rods carried by said housing, cross rods connected with the upper clamping element and slidably mounted upon the vertical rods, springs upon the vertical rods engaging the rods of 30 the upper clamping element to yieldably hold the upper clamping element in a raised

position, and securing rods for passing through the openings of the board and stationary wall above the upper clamping element to hold the upper clamping element in 50 a depressed position.

4. The structure of claim 1 having the stationary wall and clamping board provided with openings, and securing rods for passing through the openings of the board and stationary wall above the upper clamping element to hold the upper clamping element in 55 a depressed position.

5. The structure of claim 1 having the stationary wall and clamping board provided 60 with openings, and securing rods for passing through the openings of the board and stationary wall above the upper clamping element to hold the upper clamping element in a depressed position, fingers extending from 65 said securing rods and keeper means carried by the stationary wall and engageable by the fingers when the rods are turned to hold the rods against moving out of a position above the upper clamping element. 70

6. The structure of claim 1 having the clamping board provided with hanger arms, and track means carried by and extending transversely of the end walls of the housing and engaged by the hanger arms to slidably 75 and pivotally mount the clamping board.

7. An animal holding device comprising a housing including a clamping element for engaging the back of an animal, vertically disposed rods, cross rods connected with said 80 clamping element and slidably mounted upon said vertically disposed rods, springs upon said vertically disposed rods and engaging the ends of said cross rods to yieldably hold said clamping element in a raised 85 position, and means for holding said clamping element in a clamping position after being moved downwardly against the action of said springs.

In testimony whereof I have hereunto set 90 my hand.

WILLIAM L. BARLOW.
